UNITED STATES PATENT OFFICE

WALTER O. SNELLING, OF ALLENTOWN, PENNSYLVANIA

PSYCHOLOGICAL TESTING APPARATUS

Application filed October 4, 1928. Serial No. 310,236.

My invention relates to improvements in psychological testing apparatus and more particularly relates to means for testing and measuring those factors of human intelligence and manual dexterity involved in the sorting of objects of dissimilar nature. The principal object of my invention is to provide new and improved means for accurately enabling the ability to sort cards to be determined under entirely definite conditions.

Modern office procedure involves the frequent use of record cards of various types, and ability to sort cards in accordance with some predetermined characteristics is an important part of the work of many employees. One of the objects of my invention is to provide means by which the ability of an applicant for employment in such work as the sorting of cards can be determined with a high degree of accuracy and with the minimum expenditure of labor on the part of the examiner.

I have found that when a plurality of cards containing a series of sequential symbols, such as numbers running from one to sixty, or letters running from A to Z, or the names of objects running from ape to zebra, for example, are disarranged or "shuffled" until an entirely haphazard order has been produced, the time and effort required to rearrange the cards in the original orderly sequence is variable, and is dependent upon the laws of chance. For example, in shuffling a set of cards containing the letters of the alphabet from A to Z, until all semblance of the original sequential order has been lost, and then examining the sequence of the letters in the thoroughly shuffled cards, it will be found that, in one or two cases out of a thousand, in accordance with well known laws of permutations and combinations, the haphazard arrangement of the cards will, from chance alone, bear a certain partial relationship that will either notably assist or notably hinder the sorting of the cards, the order being in favor of the sorting in half of the trials, and against the sorting, in the other half of the trials. Taking the two letters M and N, for example, it will readily be seen that in one-half of any number of ran-

dom arrangements, M will precede N, and thus favor the sorting of the cards, while in the other half of the number of random arrangements, N will precede M, and thus oppose ease of sorting of the cards. What is true of these two letters, when considered alone, is equally true of every other pair of two letters, and out of say one thousand entirely random arrangements of the letters of the alphabet, in accordance with the strict rules of permutations and combinations and wholly uninfluenced by carelessness in shuffling, there will always be found a few "random" arrangements in which a considerable number of letters will bear the same order of precedence in the shuffled cards that they bore in the original sequence, while in a few cases out of one thousand entirely random arrangements, a few will be found in which, through the action of the laws of permutations and combinations, a number of letters will bear in the shuffled cards just the reverse of the order which they bore in the original orderly sequence.

From the above it will be seen that if a large number of applicants of absolutely equal sorting ability were to independently sort a large number of cards, shuffled until such cards were disarranged from the original orderly sequence and were reduced to an entirely haphazard arrangement according to the known laws of permutations and combinations, the results obtained in the testing of these applicants would not be fair, and would not truly represent the ability of the applicants to sort cards. A certain number of applicants, merely as a result of the workings of the laws of chance, would be required to sort cards in which an abnormal number of the individual cards were in the hard or reversed order from their natural arrangement in the alphabet, and an equal number of applicants would, also as a result of the working of the laws of chance, receive cards in which a considerable number of the letters were in their natural sequential arrangement as in the alphabet, or at least in the order of sequence. The letter M, for example, might not immediately precede the letter N and im-

75

80

mediately follow the letter L, but if the three letters, with other letters in between them, were in the order of L M N it will be evident that a different degree of work would be required to separate them and properly arrange them than if they were in the reverse order N M L or in the indiscriminate order N L M.

On strictly theoretical grounds it can be shown mathematically that in view of occasional favorable and occasional unfavorable arrangements that would occur in normal shuffling in accordance with the laws of permutations and combinations, no system of sorting cards from a haphazard arrangement can possibly be equally fair to a number of applicants tested, some of the haphazard arrangements being invariably easier to sort than others, and other arrangements being more difficult to sort than the average, even though the average of the hard combinations and the easy combinations equal zero.

This has led me to the conclusion that in testing sorting ability it is desirable to have the testing cards arranged initially the same for every applicant, in order that no applicant may find the cards in a more favorable arrangement than another, and one of the objects of my present invention is to enable a plurality of cards to be progressively sorted in accordance with a number of entirely different sorting arrangements, without requiring a large amount of work upon the part of the examiner in the arranging of the cards. Although this desired end may at first seem impossible of attainment, it can be readily attained by the method herein described, and a number of applicants can be tested for card sorting ability by an examiner, each applicant sorting cards from a prearranged condition to a sequential condition with respect to some certain named sequence, without requiring any sorting of the cards by the examiner for the purpose of putting such cards in the required initial order.

In the drawings forming part of this application Figure 1 represents one card of a set prepared in accordance with my present invention. Figure 2 represents another card from the same set from which the card represented in Figure 1 is taken. Figure 3 represents still another card, from the same set from which the card represented in Figure 1 and Figure 2 are taken. These cards are shown diagrammatically, and with the omission of all letters and markings that are without significance in connection with the present invention, the purpose of the drawings being to show only such markings as will enable the principle underlying my present invention to be understood. Figure 4 and Figure 5 represent cards number 12 and number 47 respectively, from a set of sixty cards of a slightly different type than the cards shown in Figure 1, Figure 2 and Figure 3.

Figure 6 and Figure 7 represent two views of a pack or deck of sixty cards, the pack or deck being provided with markings on one of its edges, corresponding to certain definite arrangements of certain symbol sequences.

The cards shown in Figure 1, Figure 2 and Figure 3 represent the first, twelfth and twenty-sixth cards, respectively, of a pack or deck of thirty cards, each card being marked with a pair of numbers separated by a hyphen, a boy's name, a weight, a distance, a girl's name, a temperature, and a date. There is no fixed arrangement upon the card for any particular symbol and therefore any particular symbol may occur in any one of the seven positions upon the card occupied by the markings shown. This pack of thirty cards may be arranged in the order of the numbers shown at the upper left hand corner of the card, or may be arranged in the order of the left hand number of the hyphenated pair, or may be arranged in the order of the right hand number of the hyphenated pair, or may be arranged alphabetically by the first letter of the boy's name, the first letter of the girl's name, etc. If an applicant receives the cards arranged numerically in ascending order of the card number as shown in the upper left hand corner of the card, and then rearranges the cards successively in the order of the first number of the hyphenated pair, the second number of the hyphenated pair, etc. until as a final act of sorting the cards are rearranged numerically in ascending order of the card number as shown on the upper left hand corner of the card, a perfectly definite task has been performed. Accordingly, the time required by any applicant to sort and resort the cards, in the manner indicated, may be used as an accurate measurement of card sorting ability, as distinguished from the less accurate measurement of card sorting ability attained by the rearrangement of cards from haphazard or shuffled arrangement as ordinarily used.

Figure 4 and Figure 5 represent two cards taken at random from a pack or deck of sixty cards, of somewhat more convenient form than the cards represented by Figure 1, Figure 2, and Figure 3. These cards are preferably of the standard 3 x 5 size used in card index files, and are divided by a horizontal central double line into an upper and lower half, each of which may contain related symbols, to be used either separately or together. Thus, for example, a set of sixty cards may be rearranged in accordance with any desired symbol shown on the top half of the card, or any desired symbol shown on the bottom half of the card, or if desired the central double line may be ignored, for the purpose of introducing a new variable, and related symbols, such as the name of a city, or a temperature or a date, may be taken from either the top half of the card or the bottom half of

the card. In all cases, however, an alphabetical or a numerical or some other definite standard of sorting is employed, so that the task of sorting is entirely definite.

5 Figure 6 and Figure 7 show a novel means that may be employed to simplify the work of the examiner or checker, in making sure that the person being examined actually correctly performs each of the sorting operations. In Figure 6 a pack of sixty cards is shown, the cards having been arranged in ascending order of the first number of the hyphenated pair, which in Figure 6 will be found on the third line below the double line, 10 in the first long square at the left hand side of the card. After the cards have once been properly so sorted, with a figure 1 before the hyphen on the top card, and a figure 60 before the hyphen on the bottom card, and 15 with all the intermediate cards sequentially arranged in accordance with ascending values of the number on the left hand side of the hyphen, a diagonal line is drawn across one edge of the card, as shown diagrammatically on the upper edge of the pack as represented by Figure 6. Figure 7 shows the same pack or deck of sixty cards, when rearranged in accordance with the last number of the hyphenated pair, a similar 20 diagonal line having been drawn across the top edge of the deck, as rearranged in this second sequential manner. It will be evident that when the cards are arranged sequentially in accordance with ascending 25 orders of the first number of the hyphenated pair, a readily visible diagonal line will appear across the left half of the top edge of the deck, while when the cards have been arranged so as to be sequentially in order of 30 ascending values of the second number of the hyphenated pair, the diagonal line on the left hand side of the top edge of the card will be broken up into a series of dots and short dashes due to proximity of one or more 35 dots, while the right hand edge of the card will show a clearly defined diagonal line, when the rearrangement of the cards by the second number of the hyphenated pair has been completed. By providing corresponding 40 diagonal lines on the sides and bottom edge of the cards, a series of readily distinguishable guides are available, each corresponding to some definite arrangement of the cards. Practical tests have indicated 45 that even one card out of its proper arrangement can be readily detected by the examiner, thus indicating any error or errors in the sorting operation, but as the marks thus made use of by the examiner appear upon the edge of the card only, and are so small as to be substantially indistinguishable when any single card is examined, apart from other cards, this edge marking is of no assistance to the person taking the test, but enables the 50 examiner by simple inspection of the edge

of the deck to determine the completeness with which the cards have been sorted in accordance with any given sequence, and to detect any error that may have been made in such sorting operation.

50 In the practice of my present invention I prefer to employ a series of from sixty to three hundred cards, each card containing a number of symbols, each symbol forming part of a sequence or series. For simplicity, 75 I will take as an example a set of twenty-six cards, as this number represents a convenient number of cards to clearly show the principles of the present invention. Each of the cards may conveniently be first given a 80 number, the first card being marked number 1, the second card being marked number 2, the third card being marked number 3, and so on in order, the last card being marked number 26. Upon the completion of the 85 marking of the numbers upon the twenty-six cards, they will form a sequence of twenty-six numbers from one to twenty-six. The cards should next be shuffled repeatedly, until they are arranged in an entirely haphazard manner, with respect to the numbers first 90 marked upon them, and when they have been disarranged to a desired condition of disorderly sequence of numbers, the cards are stacked, and upon the top card is written a 95 girl's name beginning with the letter A, such as Alice, for example, and upon the next card from the top is written a girl's name beginning with the letter B, such as Bertha, for example, the third card is similarly marked 100 with the name Clara, the fourth card with the name Daisy, etc. When all of the twenty-six cards have been thus marked, the cards will represent a number sequence, when orderly arranged from figure 1 to figure 26, 105 and a name sequence, when arranged alphabetically by girls' names, but there will be no simple relationship between the one sequence and the other. The cards should now be again shuffled thoroughly, and after stacking 110 should be marked with a third sequence, which for convenience we will assume to be a set of dates. The first card might be marked January 3, 1900, and the next card could be marked February 14, 1900, and so 115 on through the entire twenty-six cards, each one being marked with a different date, and the entire series being hereinafter called the date sequence. The cards should then be again shuffled, stacked, and each card should 120 then be given a symbol of a fourth sequence. This fourth sequence can conveniently be geographical names, the first card being, for example, marked Austria, the second card being marked Brazil, and the last card being 125 marked Zanzibar. Any desired number of additional sequential series may be given to the cards, as for example, boys' names from Adam to Zachariah, the names of chemical elements from aluminum to zirconium, 130

the names of animals from ape to zebra, etc., the number of such sequences that can be used being practically unlimited, and the cards of each sequence being entirely 5 hazard with respect to the arrangement of the symbols on the cards of any other sequence.

In employing a set of twenty-six cards made in accordance with my present invention, the cards are first arranged in orderly sequence from one to twenty-six, and are handed to the subject to be tested while so arranged. The subject is first told to arrange the cards alphabetically, according to the names of boys, and the time required to so arrange the cards is noted by the examiner. It will be observed that in the very act of sorting the cards according to an alphabetical arrangement of boys' names, the cards are necessarily rearranged as to every other sequence upon them, and as the cards start from a fixed initial arrangement to a fixed final arrangement, the work involved is exactly the same for every subject tested. Upon the subject of examination completing the rearrangement of the cards in the order of boys' names alphabetically in order, the time required for this step is again taken, and the subject is requested to rearrange the cards according to the date upon each card, the earliest date to come first, and each date to follow in date order. Again the time required is determined, and upon the completion of that step the cards are again sorted by the subject in accordance with the orderly arrangement of the next sequence. The final step in the testing is of course to have the applicant arrange the cards in numerical order by the card numbers that were first given to the cards.

When tested in accordance with the above procedure, each applicant receives the cards in exactly the same condition as every other applicant, and in each step of sorting disarranges the cards with respect to the next succeeding sequence. Upon completing the sorting of the cards according to each of the sorting operations required the cards again reach their initial condition, and as a result every applicant is faced by precisely the same task that is before every other applicant, the cards being sorted in accordance with a plurality of rearrangements from an initial condition to a final condition that is identical with the initial condition.

As an example of the application of my present invention, I will take the sorting of a set of twenty-six cards, of which the cards shown in Figure 1, Figure 2 and Figure 3 may be considered as illustrative and as representing three cards taken from a set of twenty-six. It will be noted that the positions occupied by the various symbols is not the same 60 on the different cards, with the exception of

the sequential number of the card, which for convenience should always be placed in the same position upon each card, this position being preferably at the extreme right hand end of the top line of each card. The position upon the cards of the boy's name, the girl's name, the date, the distance, the temperature, etc. should preferably be a random arrangement determined by chance. As additional variables the type used in printing the names in certain sequences, the color of ink used in printing symbols, etc. may all be changed to introduce new factors of variation.

Given such a set of cards, arranged initially in sequential order according to card numbers, each subject under examination is required to successively sort the cards in accordance with each of the series of sequence and is finally required to rearrange the cards in sequential order according to card number. Since each arrangement of the cards in orderly sequence with respect to the numbers, names and symbols of one series disarranges the cards into a given condition of disarrangement with respect to the next sequence to be employed, it will be obvious that all work on the part of the examiner in shuffling the cards is avoided, and that all errors due to the working of favorable or unfavorable arrangements according to the laws of permutations and combinations are avoided. Thus, by my invention, the two difficulties which have been inseparably connected with all previous methods of testing sorting ability are obviated, and by the use of cards as herein described the sorting ability of the different subjects can be accurately, simply and quickly determined, without any elements of chance that might either favor or oppose the subject being present.

It will be evident that many modifications may be made without departing from the spirit of the disclosure as herein made. By employing different colors in the forming of the individual symbols upon the cards as herein described, or by employing different sizes and styles of type in the printing of the symbols, either as individual symbols or as series of symbols, a vast number of sorting arrangements becomes possible, and a single pack of cards may be used for testing sorting ability ranging from such simple tasks as bringing together all cards bearing red markings, blue markings, etc., to such complicated tasks as the sorting of chemical elements in accordance with their atomic number, or the arranging of cities in accordance with their geographical location as a secondary factor of alphabetical order, and other like tasks involving a high order of intellectual ability. My invention is not limited to the type of cards as herein illustrated, as these cards have been shown for purpose of example only, and with

the object of more fully explaining the principle of my invention.

I claim:

1. A pack of psychological testing cards comprising a plurality of cards each bearing a plurality of symbols each of which forms a part of an independent sequential series of such nature that the arranging of the cards in sequential order of the symbols of any such series corresponds to the shuffling of the cards with respect to the disarrangement of the symbols of another series.
2. A pack of psychological testing cards comprising a plurality of cards each bearing a plurality of symbols each of which forms a part of an independent sequential series of such nature that the arranging of the cards in sequential order of the symbols of any such series corresponds to the shuffling of the cards with respect to the disarrangement of the symbols of every other series.
3. A pack of psychological testing cards comprising a plurality of cards each bearing a plurality of face symbols each of which forms a part of an independent sequential series of such nature that the arranging of the cards in sequential order of the symbols of any such series corresponds to the shuffling of the cards with respect to the disarrangement of the symbols of another series, and a plurality of edge symbols, each edge symbol corresponding to some face symbol of a related series.
4. A pack of psychological testing cards comprising a plurality of cards each bearing a plurality of face symbols each of which forms a part of an independent sequential series of such nature that the arranging of the cards in sequential order of the symbols of any such series corresponds to the shuffling of the cards with respect to the disarrangement of the symbols of every other series, and a plurality of edge symbols, each edge symbol corresponding to some face symbol of a related series.

In testimony whereof, I have hereunto subscribed my name this 3rd day of October, 1928.

WALTER O. SNELLING.
